UNITED STATES PATENT OFFICE.

WALTER L. KOHN AND LESSING L. KOLE, OF MILWAUKEE, WISCONSIN.

COMBINED VANITY AND MANICURE SET.

Application filed March 9, 1922. Serial No. 542,405.

To all whom it may concern:

Be it known that we, WALTER L. KOHN and LESSING L. KOLE, citizens of the United States, residing at Milwaukee, in the county 5 of Milwaukee and State of Wisconsin, have invented a new and useful Combined Vanity and Manicure Set, of which the following is a specification.

The object of our invention is to provide 10 a compact, convenient and artistic case having conveniently arranged compartments for holding various articles used in manicure and vanity sets, and to combine them in a single case. It is further our especial 15 object to provide a combination case of small size suitable for carrying in ladies' purses, and to provide a novel combination of a nail buffer securely affixed in a novel manner to the bottom of the vanity case.

20 We attain these and other objects of our invention by the mechanism illustrated in the accompanying drawings, in which:—

Figure 1 is a perspective view of the case with the top cover open;

25 Fig. 2 is a horizontal section on line 2—2 of Fig. 4 with the principal toilet articles in place in the case;

Fig. 3 is a similar section, but with the 30 toilet articles removed;

Fig. 4 is a side elevation, partly in section, with the buffer cover removed and showing the means for attaching the buffer to the vanity case;

Fig. 5 is a perspective view of the 35 principal toilet articles combined in the case; and

Fig. 6 is a detail sectional view of the powder cake and paper holder for same.

Like numerals designate like parts in each of the several views.

40 Referring to the accompanying drawings, we provide a case 1, to the bottom portion 25 of which is suitably affixed a buffer. This buffer preferably consists of a metal buffer plate 2 affixed in some suitable manner, preferably by screws 3, to the bottom 25 at each

45 end of the case. The buffer base 2 carries a suitable padded chamois or other suitable manicure buffer 4. Case 1 has an encircling recessed portion 6 frictionally engaging the 50 buffer cover 5, which is provided with opposite small integral catches 23 to positively prevent cover 5 from working loose, the outer surface of the buffer cover 5 and the main portion of the case 1 being aligned.

55 We provide a suitable rouge pad 8 and powder pad 9 mounted on opposite ends of

the case 1, said pads being packed in suitable containers 16, preferably of paper. For the purpose of holding a nail polish container 10, we provide upstanding clips 60 11 and 12 formed by turning up portions of the bottom member 25 of case 1. We further provide the series of upstanding spaced clips 14 suitably spaced apart to receive and hold a series of three cylindrical toilet articles, such as the lip stick and eye brow pencils 13 shown in the accompanying drawings.

We provide a hingedly mounted partition 17 shaped to form a cover for the toilet articles 10 and 13, while not extending over or interfering with the use of the puffs 15 at each end of the case. We provide a protective cover 18. Both cover 18 and partition 17 are mounted on case 1 by a common hinge 70 20, as shown in Fig. 1. Cover 18 is provided with a suitable integrally formed snap catch 22, as shown. Secured within cover 18 by suitable means, such as the steel plate or ring 26, we provide a mirror 19. Sufficient 80 space to form a separate compartment between partition 17 and the protective cover 18 is afforded, within which compartment a nail file 21 or any other flat toilet accessory may be placed. Case 1 is provided with a 85 circular recessed portion 27 to receive the cover 18 so that when closed the outer surface of case 1 and covers 18 and 5 will all be aligned to form a compact and attractive combination case.

90 The manner of using the device will be apparent from the accompanying drawings, the cover 5 being readily removable for permitting use of the nail buffer independently of the use of other articles in the case; and 95 the cover 18 may be opened independently of the cover 5 to permit access to the powder and rouge puffs 15; and the partition 17 may also be opened to afford access to the less frequently used articles within the 100 vanity set.

Our arrangement of securing the buffer to the vanity case provides an efficient and compact combination article which we believe will be practically indispensable to the 105 modern lady.

What we claim is:—

1. In a combined vanity and manicure set, the combination of a vanity case, a buffer affixed to the bottom of said vanity case, a 110 removable cover for said buffer, means within the vanity case for releasably holding a

7 plurality of ladies' toilet accessories, a partition hingedly mounted on the case and normally lying flat over said accessories, and a cover hinged to the case, the case having 5 a compartment between the partition and the cover.

2. In a combined vanity and manicure case, the combination of a case having opposite encircling recessed portions, opposite 10 covers frictionally and detachably engaging said recessed portions of the case, a buffer mounted on the bottom of the case and protected by one of the covers, means for releasably engaging a series of toilet articles 15 within the vanity case, a partition hingedly mounted to normally conceal the articles in the central portion of the vanity case, powder and rouge pads affixed to the end portions of the vanity set, puffs resting on 20 said pads, the puffs being removable without raising the aforesaid partition member.

3. In a combined vanity and manicure case, the combination of a case having opposite encircling recessed portions, opposite 25 covers frictionally and detachably engaging said recessed portions of the case, a buffer mounted on the bottom of the case and protected by one of the covers, means for releasably engaging a series of toilet articles 30 within the vanity case, a partition hingedly mounted to normally conceal the articles in the central portion of the vanity case, powder and rouge pads affixed to the end portions of the vanity set, puffs resting on 35 said pads, the puffs being removable without raising the aforesaid partition member, and a cover having a mirror mounted on its inner surface, said cover and partition

being mounted on a common hinge, the cover being of suitable shape to provide an additional compartment between the partition and the inner portion of the cover when closed. 40

4. In a combined vanity and manicure set, the combination of a metal case having opposite recessed encircling portions, covers releasably engaging said encircling portions to permit of the exterior surfaces of the covers and vanity case being aligned, a buffer on the bottom of the vanity case, 45 means for releasably securing the respective covers to the case, and means for releasably holding a suitable assortment of toilet accessories within the vanity case, substantially as described. 50

5. In a combined vanity and manicure set, the combination of a metal vanity case, a metal plate affixed to the bottom of said case, a manicure buffer pad affixed to said metal plate, a metal cover for said buffer, 60 spaced clips arranged on the interior of the vanity case for holding a series of ladies' toilet accessories, a hinged partition mounted in the vanity case, said partition having ends of semicircular shape to afford space at 65 each end for the removal of powder and rouge puffs without raising the partition, and a cover for the vanity case. 55

6. In combination with the apparatus described in claim 4, a mirror mounted within 70 and conforming in shape to the cover, said cover having a steel plate for holding the mirror in place, substantially as shown. 70

WALTER L. KOHN.
LESSING L. KOLE.
